UNITED STATES PATENT OFFICE

MICHAEL MELAMID, OF BERLIN-ZEHLENDORF, GERMANY

SPLITTING UP OF MINERAL OILS

No Drawing. Application filed March 12, 1925, Serial No. 15,137, and in Germany March 22, 1924.

This invention refers broadly to improvements in the splitting up of mineral oils, tar oils and of the raw material, furnishing the same, such as crude oil, crude tar and the like with a view of obtaining lower boiling hydrocarbon-compounds therefrom. In the splitting decomposition of highly boiling oils, and in particular of oils containing very highly boiling constituents of free carbon, such as coal tar, brown-coal tar and the like, it has been found to be uneconomical to effect a complete splitting-up of the raw material, in view of the fact that with the high temperatures required for this purpose the oils are liable to be decomposed with separation of carbon, thereby causing choking up of the apparatus and other inconveniences. It has, therefore, been found to be advantageous to only split up the lighter oils at a comparatively low temperature, while the unsplit portion is allowed to run off continuously.

The process is preferably carried out in the presence of hydrogen or of gases containing hydrogen, and with the utilization of a contact body which is liquefied at the temperature of reaction of which I may mention as instances, tin, bismuth, antimony, though I am not limited to these metals for the carrying out of the process of my invention, though I prefer to use them on account of the fact that they do not form carbides, and are therefore not liable to cause liberation of carbon. By this means the advantage is obtained that the lighter oils are split without residue, and without any elimination of carbon. The substances are preferably introduced into the reaction vessel as a jet or stream of material which, as soon as it is exposed to the heat of the catalyst or contact body is immediately separated into a vaporized portion, and an unvaporized liquid portion which latter containing the heavier constituents of the substances under treatment is continuously withdrawn from treatment, while the resulting vaporized portion at the prevailing high temperature of, say 300 or 400 degrees undergoes decomposition or cracking.

Example of the carrying out of the process.—100 kilograms of tar are atomized by a nozzle or the like and by means of gases, as for instance, hydrogen or gases containing hydrogen, and are introduced in the atomized condition into a vessel containing a liquid contact substance, such as tin, bismuth or antimony; the temperature is kept at about 300 to 400 degrees centigrade. The oil which has not been split up under these conditions is caused to be discharged continuously by any suitable device.

It should, of course, be understood that the invention is not restricted to this particular exemplification, and that it may be modified to better adapt it to varying conditions and within the scope and spirit of the appended claim.

I claim:—

The process of treating and splitting up coal tars containing high boiling constituents and lighter oils, which lighter oils are capable of being split up at a comparatively low temperature in order to obtain lower boiling hydrocarbon compounds therefrom, consisting in atomizing said tars with a hydrogen containing gas into a zone containing a liquid metallic catalyst to contact with said catalyst at a temperature approximately 300 to 400 degrees centigrade, thereby effecting vaporization and cracking of the lighter oils, continuously withdrawing from said zone the unvaporized high boiling constituents and separately removing the gaseous products of the cracking.

Dr. MICHAEL MELAMID.
